UNITED STATES PATENT OFFICE.

THOMAS HIGGINS, OF GLENSHAW, PENNSYLVANIA.

STRUCTURAL SHAPE.

Application filed February 18, 1922. Serial No. 537,491.

To all whom it may concern:

Be it known that I, THOMAS HIGGINS, a citizen of the United States, and resident of Glenshaw, in the county of Allegheny and State of Pennsylvania, have invented certain new and useful Improvements in Structural Shapes, of which the following is a specification.

This invention relates to metal shapes, such as I-beams and channels, and more particularly to beams of this class made from rolled metal plates, and has for one of its objects the provision of light weight shapes of this class particularly adapted for use in buildings as studding, joists, and the like.

Another object is to provide shapes formed from flat metal plates that will have flanges of double thickness and webs of single thickness, thus providing a rigid construction of comparatively light weight.

A further object is to provide shapes formed from flat metal plates in which the edges of the plates are locked against displacement.

A still further object is to provide shapes formed from flat metal plates having the novel constructions described in the following specification and illustrated in the accompanying drawings.

In the drawings, Figure 1 is an end elevation of an I-beam constructed in accordance with this invention.

Figure 2 is an end elevation of an I-beam constructed in accordance with this invention, in which the web overlies and locks the edges of the plate.

Figure 3 is an end elevation of a channel beam constructed in accordance with this invention.

Figure 4 is an end elevation of a channel beam constructed in accordance with this invention, in which the web overlies and locks the edges of the plate.

Referring more particularly to Figure 1 of the drawings, the numeral 2 designates the web of the I-beam which is of single thickness of plate, and the numeral 3 designates the flanges of the beam.

The beam is formed from a flat rolled metal plate by bending the portions 4 of the plate paralleling both longitudinal edges back upon the plate, then again bending the intervening portion of the plate upon itself paralleling the previously doubled portions, and then bending the plate at right angles at a point on a line with the

longitudinal edges of the portions 4 so as to form the web 2, so that the web portion when bent will project slightly over the edge of the portions 4 as at 5, and thus serve to lock the edges in position.

In Figure 2 a beam is shown which is formed precisely the same as the beam of Figure 1, with the exception that the web 3 is bent at right angles from a point beyond the edges of the portions 4, and thereby overlies the edges of the plate as at 6, forming a more secure lock for the edges of the portions 4.

In Figures 3 and 4 I have shown a channel beam having flanges 7 of double thickness and a web 8 of single thickness. These channel beams, like the I-beams of Figures 1 and 2, are formed from a flat rolled metal plate by first bending or doubling the portions 9 paralleling both of the longitudinal edges back upon the plate, then bending the portions of double thickness at right angles to the plane of the plate so that the edges 10 of the plate abut the single thickness of plate remaining which forms the web 8.

The beam of Figure 4 in addition to the above features, has the web portion offset or bent inwardly at 11 so as to overlie and engage the edges of the portions 9, thus firmly locking these edges against displacement.

It will be readily seen that structural shapes having the above novel features of construction will be light in weight, cheap to manufacture, and have a great utility in replacing wooden studding and joists in buildings.

While I have shown only I-beams and channel beams in the drawings, it will be understood that I do not wish to be limited either to the exact constructions nor to the particular shapes shown, since modifications that may be made without departing from the scope of my invention will readily suggest themselves to those skilled in the art.

I claim:

1. A metallic beam formed from a single flat rolled plate, comprising a web portion of single thickness and flanges of double thickness of said plate, said web portion overlying and locking the edges of the plate.

2. A metallic I-beam formed from a single flat rolled plate, comprising a web portion of single thickness and flanges of double thickness of said plate, said web por-

tion overlying and locking the edges of the plate.

3. A metallic beam formed from a single flat rolled plate, comprising a web portion of single thickness and flanges of double thickness of said plate, said flanges extending at right angles to said web, and said web portion being bent inwardly so as to overlie and engage the edges of said plate to lock them against displacement.

4. A metallic I-beam formed from a single

flat rolled plate, comprising a web portion of single thickness and flanges of double thickness of said plate, said flanges extending at right angles to said web portion, and said web portion being bent inwardly so as to overlie and engage the edges of said plate to lock them against displacement.

In testimony whereof I have hereunto set my hand.

THOMAS HIGGINS.
